TOOTHBRUSH OR SIMILAR ARTICLE

Edgar A. Phaneuf, Southborough, Mass., assignor to General Electric Company, a corporation of New York

Filed Sept. 7, 1961, Ser. No. 66,632

Term of patent 14 years

(Cl. D9—2)

FIG. 1 is a top plan view of a toothbrush or similar article embodying my new design;

FIG. 2 is a side elevational view thereof;

FIG. 3 is a perspective view thereof;

FIG. 4 is a front elevational view thereof;

FIG. 5 is a perspective view thereof on a reduced scale. The essential features of my design reside in the portions shown in full lines.

Portions of the article are broken away in FIGS. 1, 2, 3 and 4 for the convenience of illustration.

I claim:

The ornamental design for a toothbrush or similar article, substantially as shown and described.
